*Primary Examiner—Susan J. LucasAttorney, Agent, or Firm—DeWitt M. Morgan[57] CLAIM

The ornamental design for a combined lamp base and display case, as shown and described.

DESCRIPTION

FIG. 1 is a top view of my invention;

FIG. 2 is a front view thereof;

FIG. 3 is a side view, the opposite side being a mirror image;

FIG. 4 is a bottom view;

FIG. 5 is a perspective view thereof on an enlarged scale; and,

FIG. 6 is a rear view thereof.

The lamp shade and support, and figure in the display case are shown in broken lines for illustrative purposes only.
